UNITED STATES PATENT OFFICE.

JOHN KEENAN, OF CHICAGO, ILLINOIS, ASSIGNOR, BY MESNE ASSIGNMENTS, TO INTER-
TYPE CORPORATION, A CORPORATION OF NEW YORK.

SLUG-MOLD.

1,210,078.

Specification of Letters Patent.

Patented Dec. 26, 1916.

Application filed February 25, 1913. Serial No. 750,531.

To all whom it may concern:

Be it known that I, JOHN KEENAN, a citizen of the United States, and a resident of Chicago, county of Cook, and State of Illinois, have invented certain new and useful Improvements in Slug-Molds, of which the following is a specification.

My invention relates to improvements in printers' line casting machines, and has particular reference to improvements in line or slug casting molds for use upon such machines.

The object of my invention is to facilitate and cheapen the production of printing slugs, particularly that form of slug known as a skeleton slug, and to simplify and reduce the cost of the necessary parts for making skeleton slugs of different lengths.

A further object of my invention is to provide a mold by means of which skeleton slugs of different lengths can be produced without the necessity of using liners of special cross section, in other words, my object is to provide a slug mold by means of which slugs having thin portions in the bodies and wide faces can be cast of any desired length within the capacity of the mold by the use of the usual parallel thickness liners.

My invention resides in a mold for line or slug casting machines, one side of which is provided with a series of spaced recesses, openings or notches which open into the body of the mold and through the front face thereof, the intermediate portions of the mold being left intact whereby ordinary parallel thickness liners or liners unprovided with groove filling flanges can be used in conjunction therewith to produce slugs of different lengths.

My invention also consists in the various arrangements and associations of parts and in the peculiar features of construction, by means of which the above mentioned and other objects are attained, and all as herein described and particularly pointed out in the appended claims.

This present application is a continuation of my early application, Serial No. 692,432, filed April 22, 1912, and entitled "Slug molds" in so far as it relates to the subject matter thereof.

My invention will be more readily understood by reference to the accompanying drawings, in which:

Figure 1 is a perspective view of a slug

mold made in accordance with my invention and adapted for use on a line casting machine; Fig. 2 is a transverse section of the mold on the line 2—2 of Fig. 1, and showing a letter-forming matrix held in position in relation thereto; Fig. 3 is an enlarged perspective transverse section of the mold cap; Figs. 4 and 5 are perspective views of the liners; Fig. 6 is a front elevation of a portion of the mold cap; Fig. 7 is a transverse sectional view of the mold cap on the line 7—7 of Fig. 6; Fig. 8 is a transverse section of the mold cap on the line 8—8 of Fig. 6; Fig. 9 is a front elevation of a blank line or slug, such as would be cast or formed in the slug mold; Fig. 10 is a front elevation of a similar slug but having printing characters on its face; Fig. 11 is a sectional view of the slug taken on the line 11—11 of Fig. 9; Fig. 12 is a sectional view of the slug taken on the line 12—12 of Fig. 9; Fig. 13 is a sectional view of a printing slug taken on the line 13—13 of Fig. 10; and Fig. 14 is a perspective sectional view of a blank line or slug, as shown in Fig. 9.

Skeleton slugs, as heretofore produced upon line casting machines, have necessitated the equipment of the machine with a great number of expensive liners. This necessity has arisen through the fact that the skeleton slugs have been produced by means of molds which were provided with grooves extending along their faces and which grooves were adapted to form the wide faces of the skeleton slugs, and when it was desired to produce a slug of a length shorter than the extreme length of the mold it was necessary to use a liner having a flange on its front edge adapted to fill this groove, and prevent the flow of metal longitudinally along the face of the mold. These liners which are provided with the flanges are quite expensive to make, and a full complement thereof represents a very large investment. Each linotype machine carries as its standard equipment a complete set of liners which are substantially parallel in thickness and which are used for making the standard solid line-printing slugs of the different lengths required.

It has been my object to provide a mold which would be equally efficient in producing skeleton slugs and which would obviate the necessity of this complement of expensive liners, restricting the liners to what are

known as the "standard" or "parallel thickness" liners and by means of these standard liners being able to produce skeleton slugs of the various lengths desired.

5 My improved mold has the general appearance and is built up of the parts usually employed in a line casting mold employed upon linotype and similar line casting machines. It consists of a base member 2, and a cap member 3, separated from each other by a space 4 and held in position one upon the other by any suitable means, such as screws 5. The cap is held in its spaced relation from the base by means of a permanent liner or spacer 6 at one end, and a changeable liner or spacer 7 at the other end. These spacers or liners are clamped between the adjacent opposite faces of the base and cap, and are held in position by the clamping of the cap upon the base and are adapted to space the two parts of the mold apart a sufficient distance to provide a slug space 4 in which the thin portion of the slug body can be formed. So far the description would 20 apply to any standard line casting mold, and a mold which would produce a solid parallel thickness slug, the face of which is of substantially even width with the solid body of the slug. There are now being used matrix 25 characters termed "head letter" characters which have required the formation of slugs with wide faces and to accommodate these high characters, skeleton slugs have been produced to reduce the amount of metal which it is necessary to use for the production 30 of these wide-faced slugs. These skeleton slugs have faces wide enough to accommodate the highest characters associated therewith, but the body of the slug has a relatively thin portion. The slug is also provided with integral spacing bars cast with the body of the slug and adapting the slugs when assembled together to securely support each other in proper relative position. 35 As suggested above, the formation of these slugs has heretofore required the equipment of the machine with a great quantity of liners of special cross section and by means of my improvement I have been able to 40 eliminate this necessity of special liners and reduce the liner equipment of each machine to a minimum quantity of ordinary parallel thickness liners. For the purpose of producing a wide face to form a base upon 45 which to cast or support the relatively high printing characters, I provide in one member of the mold, preferably in the cap, a series of recesses, openings or notches 8 which are freely open into the slug space 4 adjacent to the front face of the mold and also through 50 the front face of the mold. I prefer to space these recesses or openings at regular intervals along the face of the mold and they are adapted to provide a series of upwardly extending projections 9 on one side 55 of the slug. The forward or front faces 10 of these projections lie in a plane with the blank face of the slug which is adapted to be cast in the mold, and the faces 10 with the adjacent face of the slug itself form a relatively wide platform or base adapted to receive and support the printing characters. These characters are adapted to be formed by the aid of matrices 11 which are provided with recesses of a form to produce the character desired. These matrices 11 are arranged in positions along the face of the mold as indicated in Fig. 2, and in conjunction with the space 4 and the recesses 8 form a space which is adapted to be filled by molten metal and thereby form a line or slug. Each matrix carries in its edge, which is presented to the mold, a depression 12 which serves to form a letter base, as indicated at 13 (Figs. 10 and 13) and a character recess 14 which is formed in the body of the metal of the matrix and opens into the base recess 12. This character recess is adapted to form a printing face 15 upon the base 13, as clearly shown in Figs. 10 and 13. 60 The base 13 of the various letters is of a width to correspond with the height of the letter which it is intended to carry, and consequently for low letters or periods this base is relatively of small dimensions while 65 for the tallest letters, which the slug is designed to carry, this base extends from one edge to the other of the slug. The spaces between the projections 9, formed on the slug, are not therefore usually completely 70 covered by the bases of the printing type. This, however, depends on the relative size of the bases and the slug upon which they are cast. The slugs illustrated in Figs. 9 and 14 are what are termed blank slugs, that is, slugs unprovided with printing characters and these would be produced if a line composed of blank matrices as distinguished 75 from letter matrices were used in the casting operation. In order that the slugs cast in the mold may be arranged in a column, and when thus arranged may be securely clamped together in proper relative position, I provide grooves 16 in the cap of the mold which 80 extend from the front face to the rear face thereof, and the upper edges of which are substantially parallel with the body of the mold. This formation or construction of the cap forms the slugs with spacing ribs 85 which serve to hold the slugs in proper relative position when they are set in a form. These slots 16 form continuations of certain of the spaces 8 and the upper edge of the slots are substantially in the plane of the upper ends of the recesses 8. The recesses 8 and the slots 16 are both tapered from their outer edges toward the body of the slug, so that the parts cast therein will readily free 90 themselves from the mold, when it is desired to eject the slug from the mold.

Slugs usually vary in length by certain definite amounts commonly in pica lengths, and I preferably form the recesses or openings 8 of such a size and spacing that the partitions 18 which separate these notches are spaced apart substantially equal with the variation in the lengths of slugs or lines desired to be produced by the mold. These partitions 18 are relatively thin and their free edges 19 and 20 are respectively flush with the lower face or bottom of the cap and with the front face thereof. Should it be desirable to make a slug of less length than the full length of the mold I insert a liner 7 at one end of the mold, which is of such a length that its inner end is spaced from the inner end of the opposite liner a sufficient distance to make a slug of the desired length, and I arrange the partitions 18 in such a manner in relation to the ends of the liners and the length of slug which it is desired to make that the inner end of the liner 7 is immediately below and in contact with one of the partitions 18, consequently when the molten metal is forced into the mold space from the rear in the usual manner and the matrices are locked in position in front of the mold the metal is prevented from flowing longitudinally along the face of the mold for it is completely stopped or dammed by the inner end of the liner 7 and the coöperating partition 18. To make slugs of different lengths, it is only necessary therefore to provide liners of the form shown in Fig. 4, that is, simple parallel thickness liners, and of the various lengths desired. It is obvious that if it is desired to design a machine to produce slugs varying by other than pica measures, that is, say varying by one-half pica measures it would only be necessary to properly space or position the partitions 18 and provide liners 7 of suitable coöperating lengths.

It will now be clear that the series of recesses 8 form what may be termed a longitudinal groove, along the front edge of the cap, divided into a plurality of small sections by the partitions 18 and that to all intents and purposes the product of the mold may be described as being a linotype slug having a thin body portion and a wide face.

As many modifications of my invention will readily suggest themselves to one skilled in the art, I do not limit or confine my invention to the specific structure herein shown and described.

I claim:

1. A slug mold having opposed sides spaced apart to form a slug having recesses in one side thereof to provide a thin portion in the slug body, one side of said mold be-

ing provided with a series of recesses extending inwardly from the forward face thereof, said recesses being separated by relatively thin walls and adapted to form a continuous series of relatively shallow projections providing a substantially continuous support for type bases which are higher than the thickness of the thin portion of the slug body as formed by the mold.

2. A slug mold in combination with a series of character forming matrices adapted for the formation of a printing slug, the mold having a space adapted to produce a slug recessed in one side to form a thin portion in the slug body and certain of said matrices having character forming spaces higher than the thickness of the mold space which forms the thin portion of the slug body, the mold being provided with laterally extending longitudinally spaced relatively shallow recesses in its forward face adapted to form laterally extending projections on the character bearing edge of the slug for supporting said high characters.

3. A mold for casting slugs for character forming matrices having character forming recesses of different heights, said mold having a space for forming a slug having recesses in one side to produce a thin portion in the slug body, said space being thinner than the height of the character forming recesses in certain of said matrices, said mold being provided with a series of spaced recesses in its forward face extending transversely from the body portion of the mold and adapted to provide transversely extending character supporting projections on the character bearing edge of the slug for supporting the characters formed in said line of matrices.

4. A slug mold adapted to coöperate with a line of character forming matrices having character forming recesses of various heights, said mold having a space adapted to form a slug having recesses in one side to produce a thin portion in the slug body, said space being thinner than the height of the character forming recesses of certain of said matrices, and the mold being provided with a series of spaced recesses in its forward face extending upwardly from the body portion of the mold and adapted to provide character supporting projections.

In testimony whereof, I have hereunto set my hand, this 28th day of January, 1913, in the presence of two subscribing witnesses.

JOHN KEENAN.
